CLAIM

The ornamental design for a peeler set, as shown and described.

Related U.S. Application Data

(63) Continuation-in-part of application No. 13/006,112,
filed on Jan. 13, 2011.

DESCRIPTION

(51) **LOC (10) Cl.** **07-04**

FIG. 1 is an exploded top perspective view of a peeler set showing our new design, including a first peeler positioned above a second peeler and incorporating exemplary peeler blades in phantom lines that form no part of the claimed invention.

(52) **U.S. Cl.**

FIG. 2 is a top perspective view of the first peeler.

USPC **D7/695**

FIG. 3 is a top view of the first peeler.

(58) **Field of Classification Search**

FIG. 4 is a front view of the first peeler.

USPC D7/680–696; 99/485, 495, 567, 568,
99/542–545, 584, 585, 588, 591–593;
30/120.1, 278, 279.2, 123.5, 123.6,
30/123.7, 279.4, 279.6, 280, 281, 282,
30/294, 155, 321, 531; 241/169, 169.1,
241/273.1–273.4

FIG. 5 is a left side view of the first peeler.

See application file for complete search history.

FIG. 6 is a right side view of the first peeler.

(56) **References Cited**

FIG. 7 is a bottom view of the first peeler.

U.S. PATENT DOCUMENTS

FIG. 8 is a top perspective view of the second peeler.
